UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Application filed April 13, 1925. Serial No. 22,660.

To all whom it may concern:

Be it known that I, MELVIN L. STONE, a citizen of the United States, and a resident of Lawrence, in the county of Essex and 5 State of Massachusetts, have invented an Improvement in Warp Stop Mechanisms for Looms, of which the following description, in connection with the accompanying drawings, is a specification, like characters on 10 the drawings representing like parts.

This invention relates to warp stop mechanisms for looms and more particularly to that type wherein a detector having a detecting movement transversely to the series 15 of drop wires is arrested when a drop wire fails to be supported by a warp thread.

It is now the common practice to support a series or row of drop wires by the warp threads during weaving, and to provide a 20 detector which may be arrested in its detecting movement by one of the drop wires when it fails to be supported by a warp thread, and thereupon effect loom stoppage. In this general type of warp stop mechanisms, the drop wires are guided in their 25 movements by drop wire guides or bars, and when a warp thread fails to support a drop wire and the loom is stopped, as indicated, it is desirable to locate the warp fault, in 30 order that the broken end or too slack warp thread may be corrected.

One of the objects of the present invention is to provide a warp stop mechanism of the above general type with a drop wire 35 guide which is normally stationary during weaving but which is moved longitudinally or lengthwise by actuation of the loom stopping means.

In accordance with the present invention, 40 therefore, the drop wire guide is associated with the loom stopping means so arranged that upon actuation of the loom stopping means the drop wire guide will be moved lengthwise and displace the fallen drop wire to thereby locate the warp fault.

The invention and new combination of parts will best be made clear from the fol-

lowing description and the accompanying drawings of one good form thereof.

In the drawings:

Fig. 1 is a perspective view of a loom equipped with the present invention;

Fig. 2 is a cross-section through the main parts of the warp stop mechanism, showing more particularly the detector or vibrator and the relation of the drop wires thereto 55 during normal weaving operations;

Fig. 3 is an enlarged transverse section of the main portions of the warp stop mechanism, showing a fallen drop wire displaced laterally or transversely of the loom when the stopping mechanism is itself actuated to stop the loom.

The advantages and results secured by the present invention are best manifested in 60 a warp stop mechanism of the general type shown and described in the patent to Carl D. Brown, No. 1,362,670, dated December 21, 1920, and in the present embodiment of the invention it is shown associated with 65 such a warp stop mechanism, although obviously, the invention may be associated with other forms of stopping means.

The loom frame 1 may be of usual construction, having the usual lay 2 which is 70 provided with a bunter 3. The shipper 4 is normally held in running position for the loom by a shoulder 5 on the shipper stand, and pivotally supported on the loom frame at 6 is a shipper knock-off, comprising an 75 arm 7 which bears against the shipper to effect loom stoppage when the knock-off is actuated.

Mounted in a suitable bearing 8 and supported by an arm 9 connected to the loom 80 frame is a rock shaft 10 having secured thereto the governor 11, and mounted for rocking and sliding movement is a dog or fish-tail 12 associated with a knock-off head 13 having a slot 14 into which projects the 85 pin 15 extending from the dog 12. The knock-off head 13 is provided with a slot 16 which embraces the shaft 10, the construction being such that should the dog 12 be

5 moved rearward by the bunter 3, the knock-off head 13 would likewise be moved rearward in the present instance, and through a connecting rod 17 joined to the knock-off lever 7 effect loom stoppage.

10 The shaft 10 is provided with an arm 18 which is connected by a rod 19 with a rocking arm 20, normally actuated by the detector or vibrator during normal operation 15 of the loom. In the present instance, the arm 20 is connected to a rock shaft 21 which has the arm 22 connected by a rod 23 with an arm 24, Fig. 1, secured to the detector shaft 25, so that on rocking movement of the detector shaft, the rock shaft 10 will be 20 rocked and control the position of the dog 12.

25 The detector shaft 25 may be given its rocking or vibrating movement through any suitable means, and as shown, it is so actuated by a rod 26 which extends downwardly and is actuated from a collar on a lower or cam shaft, as more fully shown and described in the patent to Brown, above mentioned.

30 The detector shaft has rising therefrom the detector supporting arms 27 on which is mounted the detector 28, Figs. 2 and 3. The parts so far described may be conveniently 35 and advantageously formed and associated as more fully shown and described in the Carl D. Brown patent.

35 Mounted upon the loom frame, one at each side thereof, are the supports 29 for the main portions of the warp stop mechanism, and to the supports 29 are adjustably secured the side frames 30 which are shown provided with the extended bifurcated lugs 31 resting upon the supports 29 and adjustably secured thereto by bolts 32.

40 Extending between the side frames 30 are the fixed warp supports 33, Figs. 1 and 2, each of which has at its lower portion a toothed strip 34 between which and the detector 28 a drop wire 35 may be engaged by the detector when the drop wire fails to be supported by a warp thread.

45 In the present instance of the invention, the drop wires 35 are each provided with an eye 36 through each of which extends a warp thread a normally resting on the top portion of the fixed bars 33 constituted in the present instance as warp supports.

50 The drop wires 35 may be variously contrived, but in the present instance each is shown provided with an elongated slot 37 through which extends the drop wire guide 38, whereby the drop wires are guided or directed in their movements.

55 In the present invention are shown two drop wire guides 38, but obviously, any number of such guides may be employed in accordance with the number of rows of drop wires, and each of the drop wire guides 38 carries projections which are adapted to be

60 engaged by a drop wire when it fails to be supported by a warp thread. The projections on the drop wire guides are preferably formed as teeth 39 having tapered end portions and extending upwardly from each of the drop wire guides, the construction being such that should a drop wire fail or be not supported by a warp thread, it will engage between the teeth or projections of the drop wire guide associated therewith. 70

75 In the general type of warp stop mechanism wherein the drop wires are associated with drop wire guides and a vibrating detector, the drop wire guides themselves are ordinarily fixed or secured to the side frames or supports 30, one at each side of the loom, but in accordance with the present invention the drop wire guides 38 are mounted in the side frames or supports 30 for lengthwise movement relative thereto 80 and may be conveniently held in the guideways 40 by cap plates 41.

85 During normal weaving operation, the drop wire guides 38 are stationary and act solely as a means for guiding the movement 90 of the drop wires, but in accordance with the present invention the drop wire guides are associated with the stopping mechanism which when actuated or moved to stop the loom, impart to the drop wire guide or 95 guides a movement thereof lengthwise or transversely of the loom, with the result that when the loom is stopped or arrested by the detector 28 under the influence of a fallen drop wire and the lower end thereof is caught or held between the serrated edge portion of the fixed bars 34 and the detector, the upper end portion of the fallen drop wire will be moved laterally, as indicated in Fig. 3, to indicate the warp fault. 100

105 In the present instance of the invention where two drop wire guides are shown, they are connected or joined together at their projecting end portions 42 by a bar 43 carried by a block 44 having a pin 45 extending therefrom and engaged with a slot 46 in a transversely movable arm 47, Fig. 1.

110 The arm 47 is carried by the shaft 48 which is conveniently held in a bearing 49 carried by a bracket 50 secured to the loom frame and is maintained in suitable relation to such bearing by collars 51, one above and the other below the bearing 49.

115 Extending outwardly from one of the bearings 51 (the lower one in the present instance) is a pin 52 which is engaged by a bifurcated end of a rocker 53 mounted on a rock shaft 54 supported in a bearing 55 carried by the loom frame. In the present instance, the arm 53 extends below the rock shaft 54 and is connected at 56 to an actuating rod 57 which may be suitably guided for endwise movement in the bearings 58 120 adjustably mounted on the loom frame, and the forward end of the rod 57 is positioned 125

adjacent the rear end portion of the knock-off head 13, as indicated in Fig. 1, the construction being such that should the head 13 be moved rearwardly by engagement of the 5 dog 12 with the bunter 3 on the lay, the rod 57 will be likewise moved rearwardly to thereby turn the rock shaft 48 and impart to the connected drop wire guide or guides a lengthwise movement, whereby the fallen 10 drop wire will be moved laterally, as indicated in Figs. 1 and 3, to indicate the warp fault.

During normal operation of the loom, the 15 drop wire guides will remain fixed or stationary and afford means for directing the movement of the drop wires, but when a warp thread breaks or becomes too slack, the associated drop wire will fall into the path of movement of the detector 28 and 20 thereby arrest movement of said detector and position the dog 12, through the train of mechanism described, for engagement by the bunter 3 on the lay as the latter moves backward, and loom stoppage will be effected. As the dog 12 is thus moved rearward by the bunter, the knock-off head 13 will likewise be so moved, and as the loom 25 is stopped by such movement of the knock-off head, the rod 57 will be moved lengthwise to effect lengthwise movement of the 30 associated drop wire guide or guides to move the top portion of such fallen drop wire laterally, as in Figs. 1 and 3, and thereby effectively locate the warp fault.

From the construction described it will be 35 apparent that loom stoppage is effected by the detector 28, and upon movement of the stopping means to stopping position, the drop wire guide or guides will be moved lengthwise and locate the warp fault by 40 movement of the upper end portion of the fallen drop wire laterally, while the lower end of the drop wire will be held clamped between the detector and the cooperating 45 fixed bar 34.

What is claimed is:

1. In a warp stop mechanism for looms, the combination of a series of drop wires, a drop wire guide normally stationary during weaving and having projections for engaging a drop wire when it fails to be supported by a warp thread, a detector having a detecting movement transversely of the series of drop wires, loom stopping means for stopping the loom when the detector is arrested in its movement transverse to the series of drop wires, a push bar actuated by movement of the loom stopping means, a shaft connected to the drop wire guides and rocked by the push bar to impart warp fault locating movement to the drop wire guide.
2. In a warp stop mechanism for looms, the combination of a row of drop wires, a drop wire guide normally stationary during weaving, a vibrating detector below the drop

wires, loom stopping means including a dog rendered operative by lay movement to stop the loom when a drop wire arrests the detector, and connections between the dog and drop wire guide to impart warp fault locating movement to the drop wire guide by operative movement of the dog by the lay. 70

3. In a warp stop mechanism for looms, the combination of a row of drop wires, a drop wire guide mounted for longitudinal movement and normally stationary during weaving, a vibrating detector below the drop wires, loom stopping means rendered operative to stop the loom when a drop wire arrests the detector, a rock shaft connected to the drop wire guide and connections between the loom stopping means and rock shaft to impart warp fault locating movement to the drop wire guide by operative movement of the rock shaft by the 80 loom stopping means.

4. In a warp stop mechanism for looms, the combination of a series of drop wires, a normally stationary drop wire guide, a detector having a detecting movement, a dog positioned for engagement by the lay to stop the loom when the detector is arrested by a drop wire, a rock shaft mounted for rocking movement adjacent the warp stop mechanism, and connected to the drop wire guide, and a rod between the rock shaft and dog for imparting movement to the drop wire guide by lay movement of the dog. 90

5. In a warp stop mechanism for looms, the combination of a series of drop wires, a drop wire guide, a vibrating detector movable transversely of the series of drop wires, a fixed bar against which the detector holds a drop wire when it fails to be supported by a warp thread and the detector is arrested, a loom stopping dog adapted to be engaged and moved lengthwise by the lay when the detector is arrested by a drop wire, a rod adapted to be moved by lay induced movement of the dog, and means between the dog and drop wire guide for moving the drop wire guide lengthwise when the dog is moved lengthwise to thereby locate the warp fault. 100

6. In a warp stop mechanism for looms, the combination of a series of drop wires, a drop wire guide, a detector having a detecting movement, loom stopping means including a dog, the lay having a bunter, connections between the dog and detector for operatively positioning the dog for engagement by the bunter when the detector is arrested by a drop wire, and means actuated by the dog when moved by the bunter to displace the drop wire guide and locate the warp fault. 120

7. In a warp stop mechanism, the combination of a series of drop wires, a drop wire guide having teeth to engage a drop 130

wire, a detector having a detecting movement, the lay having a bunter, stopping means including a dog controlled by the detector and positioned for movement by the
5 bunter when the detector is arrested, and means actuated by movement of the dog for imparting lengthwise movement to the drop wire guide to locate the fallen drop
wire.

10 8. In a drop wire mechanism for looms, the combination of the lay having a bunter,

a dog for engagement by the bunter, a shipper knock-off adapted to be actuated by the dog when moved by the bunter, a series of drop wires, a drop wire guide, a detector 15 for controlling the dog, and means actuated by the dog for moving the drop wire guide to locate the warp fault.

In testimony whereof I have signed my name to this specification.

MELVIN L. STONE.
